UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

PUMP.

1,297,441.

Specification of Letters Patent. Patented Mar. 18, 1919.

Application filed July 8, 1914. Serial No. 849,646.

To all whom it may concern:

Be it known that I, MATTHEW T. CHAPMAN, a citizen of the United States, residing at Aurora, in the county of Kane, State 5 of Illinois, have invented certain new and useful Improvements in Pumps, of which the following is a specification, reference being had to the accompanying drawings.

My invention relates to pumps and particularly to that class of pumps employing three independently-actuated plungers. It is one of the objects of my invention to provide new and improved means for actuating the plungers of a pump of this type by the 10 use of which a simple cheap construction is attained avoiding all side strain upon the plunger-rods. It is another object of my invention to provide actuating means of this type which shall be very strong and not 15 likely to become distorted or broken through use. It is another object of my invention to provide actuating means of this type such that each plunger in turn is started upon its operative upward stroke before the end 20 of the upward stroke of one of the other plungers, whereby the upwardly-moving column of water is kept constantly in motion thus avoiding the necessity of starting the column of water into motion at each 25 stroke of the plunger. It is another object of my invention to improve devices of this type in sundry details hereinafter pointed out.

In the drawings,—

35 Figure 1 is a side view of the mechanism at the mouth of the well by which the plungers are actuated;

Fig. 2 is a front view of the parts shown in Fig. 1;

40 Fig. 3 is substantially a cross-section taken on line 3—3 of Fig. 2;

Fig. 4 is a plan view of the crank mechanism;

45 Fig. 5 is a cross-section taken on line 5—5 of Fig. 4; and

Fig. 6 is a sectional view showing the connections of the plunger rods with the plungers or pistons below the water in the pump tubing.

50 Referring to the several figures of the drawings, in which corresponding parts are indicated by the same reference characters,—

10—11 indicate standards connected at 55 their upper ends by a yoke 12. Mounted in

suitable bearings in the upper ends of the standards 10—11 is a shaft 13 having keyed or otherwise fixed thereon two spiral gears 14—15. Mounted in brackets 16 of any suitable type is a shaft 17 having fixed thereon 60 spiral gears 18—19 meshing with the gears 14—15, respectively. The shaft 17 is adapted to be driven for the purpose of rotating the gears 14—15 through the medium of a gear 19 mounted upon said shaft meshing 65 with a gear 20 mounted upon the shaft of a motor 21 of any suitable type supported from the framework by a bracket 22.

Referring now particularly to Figs. 4 and 5, 23—24 indicate double-armed brackets 70 fixed upon the shaft 13 having mounted between them at one end a pin 25. Fixed upon the shaft 13 adjacent to the bracket 23 is an arm 26 connected at its outer end to the outer end of one of the arms of the 75 bracket 23 by means of a pin 27. Fixed upon the shaft 13 adjacent to the bracket 24 is an arm 28 having its outer end connected by means of a pin 29 with the outer end of one of the arms of the bracket 24. 80

Referring now to Fig. 3, 30 indicates a crank-box, which, in the construction shown, is formed of two parts secured together by suitable bolts. The crank-box 30 is provided with a horizontally-positioned slide-box 31 thereacross along which a slide-block 32 mounted upon the pin 25 is adapted to slide as the pin 25 is revolved about the shaft 13 by the motor 21. The crank-box 30 is also provided with a vertically-positioned slot 33 so that the crank-box 30 is 85 adapted to move up and down relative to the shaft 13 as said shaft is rotated. The crank-box 30 is also provided with an upwardly-extending rod 34 which passes through a suitable slide-bearing in the yoke 12, the rod 34 serving to guide and to steady the crank-box 30. Suitably connected to the lowermost portion of the crank-box 30 is a pump rod 35 which is connected with a suitably-valved plunger or piston 36 located 90 down in the well within the pump casing 37. 38—39 indicate crank-boxes similar in a general way to the crank-box 30. The crank-box 38 is provided with a guide rod 40 at its upper end working in a suitable slide-bearing in the yoke 12 and has connected to its lower end a downwardly-extending rod 41. In the slide-box of the crank-box 38 is mounted a slide-block 42 (see 100

105 40 at its upper end working in a suitable slide-bearing in the yoke 12 and has connected to its lower end a downwardly-extending rod 41. In the slide-box of the crank-box 38 is mounted a slide-block 42 (see 110

Fig. 1) which works upon the pin 27, whereby the crank-box 38 is reciprocated up and down by said pin 27 as the shaft 13 is rotated. The crank-box 39 is provided with 5 a rod 43 rising from its upper end and having a suitable slide-bearing in the yoke 12, said crank-box being provided at its lower end with a downwardly-extending rod 44. In the slide-box of the crank-box 39 is 10 mounted a slide-box 45 (see Fig. 3) working upon the pin 29, whereby the crank-box 39 is reciprocated up and down by said pin upon the rotation of the shaft 13.

Mounted upon the lower ends of the rods 15 41-44 is a cross-head 46 adapted to be reciprocated by said rods, together with a hollow plunger rod 47 connected thereto, within which hollow plunger rod 47 the plunger rod 35 is located. The plunger rod 47 is connected at its lower end with a suitably-valved plunger or piston 48 located and adapted to be reciprocated in the pump-casing 37 a short distance above the plunger 36.

Inasmuch as the crank-box 30 does as 25 much work as the two crank-boxes 38 and 39 together, the crank-box 30 is made considerably wider and heavier than either of the two coöperating crank boxes.

Upon the gears 14-15 are mounted wrist-pins 49-50, respectively, adapted to operate 30 connecting rods 51-52 connected at their lower ends to a cross-head 53 which is slideable up and down through suitable slots 54 in the standards 10-11. The cross-head 53 has connected to it a hollow pump rod 55 in 35 which the pump rods 35 and 47 are located. The pump rod 55 has mounted upon its lower end a suitably-valved piston or plunger 56 working in the pump casing 37 a short distance above the piston 48.

As is best shown in Figs. 1 and 5, the pin 25, the pins 27 and 29, and the pins 49 and 50 are arranged in triangular relation relative to each other,—that is to say, at the 45 points of an equilateral triangle through the center of which the shaft 13 passes. By reason of this arrangement one of the pistons 36-48-56 is being moved upward all of the time during the rotation of the shaft 13, and 50 well before the end of the upward stroke of each piston the next-succeeding upwardly-moving piston is started on its operative upward stroke, thus keeping one of the three pistons moving upward all of the time at a 55 comparatively high rate of speed. In this way the column of water is raised at substantially a uniform speed throughout its upward movement, thus avoiding the stopping and starting of the column of water at 60 each stroke.

By the use of spiral gears for driving the

shaft 13, the intermeshing gears are maintained continuously in contact thus preventing jar in the operation of the device.

Upon the rotation of the shaft 13, the 65 slide-blocks 32, 42 and 45 are carried by the pins 25, 29 and 27, respectively, around the said shaft, the slide-blocks moving back and forth in the slide-boxes 31. The said slide-blocks are of such a length that when one of them is extended across the slot 33 of its crank-box the projecting end of the block is brought into operative engagement with the slide-box on the far side of the slot before the actuating pin 25, 27 or 29 is brought into 75 alignment with the slot. The device is thus insured against cramping and the power is applied very efficiently to the plunger rods directly in the line of such rods.

By reason of my construction and arrangement, I have provided for a pump an exceedingly strong actuating mechanism, obtaining a crank motion without the necessity for cutting out or offsetting the crank shaft. So far as I am aware, this is new in pumps 85 of this type, and the claim is to be construed accordingly.

While I have shown my slide-boxes 31 all arranged in horizontal position, it will be understood that I do not wish to limit 90 myself to that particular feature of construction except as hereinafter specifically claimed, it being understood that the slide-boxes may be set at any desired angle without departing from my invention.

What I claim as my invention and desire to secure by Letters Patent, is—

In a pump, the combination of a shaft, two arms fixed upon said shaft and extending therefrom, a wrist pin mounted in the 100 ends of said arms and adapted to be revolved about said shaft, two other arms mounted upon said shaft and extending therefrom at an angle of approximately 120 degrees from said first-named arms, a second wrist pin 105 mounted in the ends of said second-named arms and adapted to be revolved about said shaft, a slide-block journaled upon each of said pins, slide-boxes in which said slide-blocks are adapted to be reciprocated, each 110 of said slide-boxes being parted at an intermediate point for passing said shaft, a plunger rod connected to each of said slide-boxes, a crank-arm mounted on one end of said shaft and extending therefrom at approximately 120 degrees from said first and second-named arms, and a plunger rod connected to said crank-arm.

MATTHEW T. CHAPMAN.
